175,230

COMBINED MILEAGE AND COIN KEEPER

Archie A. Paseka, Lansing, Mich.

Application November 12, 1954, Serial No. 33,081

Term of patent 14 years

(Cl. D14—6)

FIG. 1.

FIG. 2.

FIG. 3.

FIG. 4.

Figure 1 is a front view in perspective of a combined mileage and coin keeper embodying my new design;

Figure 2 is a top view;

Figure 3 is a rear view thereof; and

Figure 4 is a side view thereof.

I claim:

The ornamental design for a combined mileage and coin keeper, as shown.
